Primary Examiner — April Rivas*Assistant Examiner* — Tia Ruth-Renee Polidori(74) Attorney, Agent, or Firm — Apex Juris, PLLC; R. Lynette Wylie(57) CLAIM

The ornamental design for a pan support, as shown and described.

DESCRIPTION

FIG. 1 is a perspective view of a pan support;
FIG. 2 is a front view thereof; a rear view thereof is a mirror image;

FIG. 3 is a left-side view thereof; a right-side view thereof is a mirror image;

FIG. 4 is a top view thereof;

FIG. 5 is a bottom view thereof; and,

FIG. 6 is a perspective view thereof.

The portions of the pan support shown in broken lines form no part of the claimed design.

1 Claim, 6 Drawing Sheets(56)
